UNITED STATES PATENT OFFICE.

RICHARD EBENEZER WESTON, OF WATFORD, ENGLAND.

ADDING-MACHINE.

SPECIFICATION forming part of Letters Patent No. 765,531, dated July 19, 1904.

Application filed February 29, 1904. Serial No. 195,882. (No model.)

To all whom it may concern:

Be it known that I, RICHARD EBENEZER WESTON, gentleman, a subject of the King of Great Britain, residing at Grove Lodge, Clarendon Road, Watford, in the county of Hertford, England, have invented a certain new and useful Adding-Machine, of which the following is a specification.

This invention relates to adding-machines especially suitable for markers for games, such as "bridge." The total is shown by an indicator, which is preferably in the form of a hand revolving on a dial, but which may be a disk or cylinder or other arrangement, such as those used for revolution-counters. Generally two concentric hands are employed geared together in a similar manner to the hands of a clock, one hand recording units and the other hundreds.

According to this invention the units-indicator when driven forward is locked to a subsidiary indicator, preferably concentric with it, such indicator being provided with a spring which carries it back to zero when released without moving the units-indicator backward, so that each time the subsidiary indicator is turned from zero to some number on the dial that number is added to the total shown.

The drawings show a bridge-marker made according to this invention.

Figure 1 is a face view. Fig. 2 is a section by a plane parallel to the face; and Figs. 3 and 4 are sections on the lines 3 3 4 4, Fig. 2. Fig. 5 shows a detail.

a is the subsidiary hand, *b* the units-hand, and *c* the hundreds-hand.

The hand *a* is fixed to a spindle *a'*, which also has fixed to it a toothed disk *a²* and a heart-shaped cam *a³*, Fig. 5. The hand *b* is fixed to a sleeve *b'* on the spindle *a'*.

b² is a toothed disk turning with the sleeve *b'*, but free to move along it. This disk normally engages with the disk *a²*, the two disks thus forming a clutch.

b³ is a pinion fixed to the sleeve *b'* and gearing with a wheel *d*, which is driven by a pinion *e²*, fixed to a spindle *e'*, which can be turned by a handle in the form of the thumb-nut *e*.

f is a lever pivoted at *f'* and forked at its

two ends to embrace the spindle *e'* and engage with a groove in the stem of the disk *b²*.

f² is a spring which presses the lever *f* against the pinion *e²*.

h is a lever carrying a roller *h'*, which is pressed by the spring *h²* against the heart-shaped cam *a³*.

b⁴ is a disk fixed to the sleeve *b'*, and *b⁵* is a spring pressing it upward, thus acting as a brake to the gearing and preventing backlash.

When the nut *e* is turned, it drives the pinion *b³*, (through the pinion *e²* and wheel *d*,) and the hands *a* and *b* are turned together through the same angle, while the lever *h* is turned against its spring *h²* by the heart-shaped cam *a³*. When the nut *e* is pressed downward against the spring *f²*, the lever *f* lifts the disk *b²* out of engagement with the disk *a²*, so freeing the latter, whereupon the pressure of the roller *h'* upon the cam *a³* turns the hand *a* back to zero, the hand *b* remaining stationary.

The hand *c* is fixed to a sleeve *c'* on the sleeve *b'* and to which a wheel *c²* is fixed. This wheel gears with a pinion *d'*, fixed to the wheel *d*.

j and *k* are pointers for scoring the games tricks, respectively.

What I claim is—

1. The combination of an indicator, a subsidiary indicator, a handle free to rotate and to move endwise, gearing connecting the handle to the first indicator and transmitting its rotary motion in either direction to it, a clutch locking the two indicators together and mechanism operated by the endwise movement of the handle for releasing the clutch.

2. The combination of an indicator, a sleeve fixed to it, a handle movable axially, a pinion fixed to the handle, a train of gearing connecting the pinion to the sleeve, a subsidiary indicator, a spindle carrying it and working in the sleeve, a clutch one member of which is mounted on the sleeve and the other on the spindle, a lever turned by the axial movement of the handle and operating the clutch and a spring tending to turn the subsidiary indicator backward.

3. The combination of an indicator, a sleeve fixed to it, a handle movable axially, a pinion fixed to the handle, a train of gearing connecting the pinion to the sleeve, a subsidiary indicator, a spindle carrying it and working in the sleeve, a clutch one member of which is mounted on the sleeve and the other on the spindle, a lever turned by the axial move-

ment of the handle and operating the clutch, a heart-shaped cam fixed to the spindle, a lever bearing against the cam, and a spring operating the lever.
